UNITED STATES PATENT OFFICE.

EDSEL B. FORD, OF DETROIT, MICHIGAN.

DESIGN FOR A RADIATOR SHELL.

Application filed February 13, 1928. Serial No. 25,425. Term of patent 14 years.

To all whom it may concern:

Be it known that I, EDSEL B. FORD, a citizen of the United States, residing in the city of Detroit, in the county of Wayne and State of Michigan, have invented a new, original, and ornamental Design for Radiator Shell, of which the following is a specification, reference being had to the accompanying drawings, forming part thereof.

Figure 1 is a front elevation of a radiator shell, showing my new design.

Figure 2 is a side elevation of my radiator shell, and

Figure 3 is a top or plan view of my radiator shell.

I claim:

The ornamental design for a radiator shell, as shown.

February 3, 1928.

EDSEL B. FORD.
